UNITED STATES PATENT OFFICE.

WILLIAM A. BRISTOR, OF INDIANAPOLIS, INDIANA.

SHOE.

SPECIFICATION forming part of Letters Patent No. 296,518, dated April 8, 1884.

Application filed December 18, 1883. (No model.)

To all whom it may concern:

Be it known that I, WILLIAM A. BRISTOR, of the city of Indianapolis, county of Marion, and State of Indiana, have invented certain new and useful Improvements in Shoes, of which the following is a specification.

The object of my said invention is to produce a shoe which shall combine the pliability of a hand-made "turned" shoe at the toe or front portion with the rigidity of a machine-made shoe at the shank and heel portions, whereby certain advantages both in quality and cost of production are secured, as will be presently described. This object is accomplished by first preparing the sole and upper in the same manner as when they are to be sewed and turned by hand, and then sewing them together from the toe back along both sides of the ball. Then, instead of continuing the sewing by hand, the shoe is turned, a steel shank and a half-insole inserted, and the remainder of the stitching done by machine in the same manner that the sewing is done in ordinary machine-made shoes.

Referring to the accompanying drawings, which are made a part hereof, and on which similar letters of reference indicate similar parts, Figure 1 is a perspective view of a shoe embodying my invention, a portion of the upper being broken away to show the interior; Fig. 2, a longitudinal section, on an enlarged scale, of the sole of the shoe; Fig. 3, a cross-section on the dotted line *z z*; Fig. 4, a cross-section on the dotted line *y y*, and Fig. 5 a perspective view of the shoe when the construction is so far advanced that the shoe is ready to turn.

In said drawings, the portions marked A represent the sole of the shoe; B, the inner half-sole; C the shank, and D the upper. The sole A is first secured to the upper B by a row of hand-stitches, *a*, while the shoe, so far as completed, is wrong side out, as shown in Fig. 5. The shoe is then turned, the ordinary shank C, the half-insole B, and the counter D' are placed in position, and the several parts are secured together by the row of machine-stitches *b*. The whole sole is then usually covered by an ordinary lining, (not shown,) and the shoe finished in the ordinary manner.

It is, as is well known, very desirable that the ball or front portion of the sole be flexible, both because a flexible sole is more durable and because it is easier on the foot of the wearer. It is also desirable that the shank and counter shall be strong and stiff. Heretofore the flexibility of the ball and rigidity of the shank and counter could not be combined satisfactorily, for the reason that a shoe stitched entirely by hand before turning cannot be provided with a steel shank at all, and the counter must be lighter than desirable. The consequence is that hand-made shoes of this character are easily "broken down" in the instep, and "run over" at the heel. A shoe wholly machine-made must have an insole extending entirely to the toe, and consequently the ball of such a shoe lacks the desired flexibility, besides which the stitches, being nearer the center, are apt to hurt the feet of the wearer, which the hand-made stitches, being at the extreme edge, will not do. By hand-stitching only around the ball of the sole and then turning the shoe and completing the process of manufacture in the manner described the ball is left flexible and the shank and heel are made as stiff and strong as is desired. By this construction it is also rendered possible to use a heavier sole when desirable than has been possible with ordinary hand-made turned shoes, and, it being only a single sole of the better quality of leather used for outer soles it is much more durable than the heavier double soles employed in machine-made shoes. Besides producing a superior article, the cost of manufacture is also materially lessened, as hand-stitching is much more expensive than machine-stitching.

Having thus fully described my said invention, what I claim as new, and desire to secure by Letters Patent, is—

1. The process of making shoes which consists, first, in stitching the ball of the sole and toe of the upper together while wrong side out, then turning the shoe, then placing the insole, shank, and counter in position, then completing the stitching and afterward finishing the shoe in the ordinary manner, substantially as set forth.

2. The combination, in a shoe, of the sole

A, the upper D, the rear half-insole, B, the shank C, and counter D', said several parts being constructed, arranged, and secured together substantially as shown and specified.

5 3. A shoe the forward portion of which is stitched together by a row of stitches at the outer edge of the sole, and the remaining portion of which is stitched together by a row of stitches nearer the center of the sole, both said seams being inside the point where the

sole and upper come together, substantially as described, and for the purposes specified.

In witness whereof I have hereunto set my hand and seal, at Indianapolis, Indiana, this 10th day of December, A. D. 1883.

WILLIAM A. BRISTOR. [L. S.]

In presence of—

E. W. BRADFORD,
CHAS. L. THURBER.
